No. 618,204.

Patented Jan. 24, 1899.

E. A. HAUERWAS.

AIR BRAKE.

(Application filed June 9, 1897.)

(No Model.)

UNITED STATES PATENT OFFICE.

EDGAR A. HAUERWAS, OF SARATOGA SPRINGS, NEW YORK, ASSIGNOR OF
ONE-HALF TO CHARLES D. HAMMOND, OF ALTAMONT, NEW YORK.

AIR-BRAKE.

SPECIFICATION forming part of Letters Patent No. 618,204, dated January 24, 1899.

Application filed June 9, 1897. Serial No. 639,969. (No model.)

To all whom it may concern:

Be it known that I, EDGAR A. HAUERWAS, residing at Saratoga Springs, in the county of Saratoga and State of New York, have invented a new and useful Air-Brake, of which the following is a specification.

My invention relates to air-brakes, and has for its object to furnish for attachment to the well-known automatic air-brakes improved means for controlling the escape of air from the brake-cylinder.

With this object in view my invention consists in the improved construction, arrangement, and combination of parts hereinafter fully described, and afterward specifically pointed out in the claims.

In order that persons skilled in the art to which my invention most nearly appertains may make and use the same, I will now proceed to describe its construction and operation in connection with the accompanying drawings, forming a part of this specification, in which—

Figure 1 is a sectional view of so much of the well-known Westinghouse air-brake as is necessary to illustrate my invention and its application thereto. Fig. 2 is a detail sectional view on the line 2-2 of Fig. 1. Fig. 3 is a sectional view showing the retaining-valve in open position with my improved lifter attached thereto. Fig. 4 is a sectional view showing the same parts in closed position. Fig. 5 is a sectional view through my improved escape-valve. Fig. 6 is a detail perspective view of the locking device for the rubber-seated valve.

Like letters of reference mark the same parts wherever they occur in the different figures of the drawings.

Referring to the drawings by letters, A is a pipe under the car, forming part of the main train-line, through which the pressure is communicated from the main reservoir on the engine to the auxiliary reservoirs of the cars. The communication from this line to the auxiliary reservoir B is through the branch pipe C and the valves E and F of the arrangement of valves at D, E, and F, known as the "triple-valve," and thence through branch pipe G, the valve D, known as the "rubber-seated valve," being a medium of

communication between the train and the brake-cylinder H, all of these parts being of the usual construction and operated in the usual manner.

When the valve F is in its "released" position, which occurs when the pressure on the train-line side of piston F is greater than the pressure from the auxiliary reservoir on the opposite side of said valve, there is open communication between the outside of the brake-piston, as at I, and the escape-pipe J and retaining-valve K through ports I' and I², as shown in Figs. 1 and 2.

The retaining-valve K is a weighted, or it may be a spring-seated, valve which opens when the pressure under it becomes great enough to raise it, which act of opening permits the escape of air from this valve through any suitable port, as at K', Fig. 3, and reduces the pressure in front of the brake-piston in the brake-cylinder. This valve has heretofore been supplied with no means for operating it except this pressure under it. It is desirable under certain circumstances that some other means for opening it not dependent upon such pressure be provided—for instance, when it is desired to permit the escape of all pressure in the brake-cylinder or any part thereof less than sufficient to raise the valve, such circumstances arising especially on a road in mountainous or hilly districts where there are numerous grades. On such roads it is extremely desirable that the engineer have entire control of the pressure in the brake-cylinder, and to give him this control is the especial object of my invention.

To accomplish this, I provide electromagnets L L, located above the retaining-valve, which is made of iron or other magnet-attracting metal, the electric line M for energizing such magnets being supplied with current from suitable batteries or dynamos located at any preferred position on the train or engine. The line extends from the source of current and magnets to the cab of the engine or to any desired station on the car or train within reach of the engineer of a steam-railway train, the motorman of an electric train or car, or any other person to whom the control of the brakes is assigned.

The circuit is an open one and at the con-

trolling-station is provided with suitable circuit-closers, such controlling-station being herein represented as in the cab of an engine, in connection with the handle N of the engineer's valve, by means of which the pressure from the main reservoir O and in the train-line is controlled. On this handle N, far enough from the end thereof to leave free space sufficient for the engineer to grasp the handle, especially as is sometimes hurriedly done in certain emergencies, without interfering with the electric current, is placed a circuit-closer P, which is so arranged, in any well-known or preferred manner, as to close the circuit when pressed toward the handle and provided with means to automatically break the circuit when released from said pressure. With this arrangement the engineer will have absolute control over the pressure in the brake-cylinder when such pressure is insufficient to open the valve against the weight thereof or the closing-spring when a spring-seated valve is used.

In ordinary use of this class of air-brakes small particles of dirt or debris of various kinds sometimes lodge between the rubber-seated valve D and its seat, causing a small continuous leak until removed. Such removal cannot be made while the train is running, and a provision for neutralizing the effect of such leaks while the train is in motion is very desirable. This I accomplish to a great extent by the provision of an escape-valve Q, attached to the escape-pipe J. This valve (illustrated in detail in Fig. 5) consists of a casing or cylinder R, having an inward-projecting annular flange R' and a small escape-port R² in the end. Its piston S has a small notch S' in one edge, forming a port, and is held in position against inside pressure by a light spring S². When the air-pressure upon this piston due to leakage, as before set forth, is not sufficient to overcome the resistance of the spring, the ports S' and R² will remain open and permit of its free escape; but when it is sufficient to overcome the resistance of the spring the piston will be forced to seat itself against the flange R', which projects a sufficient distance inward to cover and close the port S' in the piston, thereby also cutting off communication between the inside of the cylinder R and the port R², effectually closing both ports. For effectually closing a very

bad leak in the rubber-seated valve I provide other means, as shown at T in Figs. 1 and 6, 55 which consists in a key, provided with a suitable handle, which key when turned one way has no effect, but when turned at right angles to its idle position serves to lock the rubber-seated valve D and the check-valve D' 60 firmly in their seats, positively closing them.

To lock the retaining-valve in an open position, I provide a key U, which when turned upward will hold the valve out of contact with its seat.

While I have illustrated and described the best means now known to me for carrying out my invention, I wish it to be understood that I do not desire to restrict myself to the exact details of construction shown, but hold that any such slight changes and variations of such details as would suggest themselves to the ordinary mechanic would properly fall within the limit and scope of my invention.

Having thus fully described my invention, what I claim as new, and desire to secure by Letters Patent of the United States, is—

1. In an automatic air-brake, the combination with the brake-cylinder and the retaining-valve, of an escape-valve adapted to be closed by overpressure located between the said cylinder and valve, substantially as set forth.
2. In an automatic air-brake, the combination with the brake-cylinder, the retaining-valve and the retaining-valve pipe, of an escape-valve on said pipe adapted to be closed by overpressure, substantially as set forth.
3. In an automatic air-brake, the combination with the brake-cylinder, the retaining-valve, and the retaining-valve pipe, of an escape-valve on said pipe provided with a spring-controlled piston, adapted to be closed by overpressure, substantially as set forth.
4. In an automatic air-brake, an escape-valve, consisting of a cylinder having a small port in its end and an annular, inward-projecting flange, in combination with a piston having a notch in its periphery, and a spring acting to hold the piston against a given pressure but to be overcome by excessive pressure, substantially as set forth.

EDGAR A. HAUERWAS.
